GASEOUS CONDUCTION DEVICE

Robert E. Barclay, Chicago, Ill., assignor to Federal Electric Company, Inc., Chicago, Ill., a corporation of New York

Application July 8, 1935, Serial No. 30,305

35 Claims. (Cl. 176—122)

My invention relates in general to lamps and has more particular reference to the provision of a lamp adapted to produce illumination substantially identical to daylight.

5 An important object of the invention is to utilize a plurality of light sources, each producing a daylight component and all associated so that the components may blend together and produce a resultant light that can be distinguished from 10 daylight only by precise scientific measurement.

Another important object is to utilize electrical discharge illumination for the purpose of artificially producing approximate daylight.

Another important object resides in utilizing 15 electrical discharge in a plurality of ionized gaseous fields, including mercury, cadmium preferably with a trace of gallium, and neon for the purpose of producing approximate daylight.

Another important object is to utilize crypton, 20 argon or xenon gas as a carrier for mercury and cadmium vapors in a discharge device, crypton being preferably used as a mercury carrier and xenon as a carrier for cadmium.

Another important object is to provide a lamp 25 having a plurality of discharge channels, each of which channels contain a different gaseous media, and having different cross-sectional areas in order to obtain a desired intensity of illumination in the various media in response to electrical discharges, in said several media, at predetermined potentials and currents and thus to 30 produce combined light having desired intensity of the several components.

Another important object is to determine the 35 quality of artificially produced light by determining the cross-sectional area of electrical discharge paths in various gaseous conduction media employed to produce components of the synthetic light.

Another important object resides in producing 40 synthetic light, comprising several components produced by electrical discharge in corresponding gaseous media, by enclosing several of the gaseous media, each in a separate channel 45 formed in a sealed envelope, the separate channels being separated by a partition, preferably integral with the envelope, so that electrical discharge in one channel may be aided by heat developed as a result of electrical discharge 50 in another of the channels in order thus to improve the operating efficiency of the device as well as to intimately associate the sources of the components of the resultant synthetic illumination so produced.

55 Another important object is to provide a day-

light lamp comprising closely associated sources of light components wherein said sources comprise various selected gaseous media adapted to be excited by electrical discharge; a further object being to employ mercury vapor, cadmium vapor, and neon gas as the sources of artificial 5 sunlight components.

Another important object is to enclose each of the gaseous media in envelope means defining a separate chamber or compartment for each 10 of the media employed as a component light source; a further object being to integrate the envelope means containing certain of the media while another of the gaseous media is contained in an envelope separate from the integrated envelope; a still further object being to integrate 15 the envelopes containing the mercury and cadmium vapors to form a unitary lamp element while arranging the envelope, containing neon gas, to encircle or embrace the unit containing the mercury and cadmium vapors. 20

Mercury vapor, when excited, produces a characteristic blue light, cadmium vapor produces green, while neon gas emits a reddish light, and the invention contemplates the control of intensity of these components by regulating the cross-sectional area of the chambers containing the gases as well as the potential at which the 25 gas-exciting discharge is accomplished.

Numerous other objects, advantages, and inherent functions of the invention will become apparent from the following description, which, taken in connection with the accompanying drawing, discloses preferred embodiments of the 30 invention.

35 Referring to the drawing:

Figure 1 is a perspective view of a tubular element providing a plurality of gaseous conduction channels and adapted to be utilized in forming a lamp embodying my present invention.

Figure 2 is a sectional view taken substantially 40 along the line 2—2 in Figure 1.

Figure 3 is a perspective view of a lamp for 45 artificially producing daylight in accordance with my present invention.

Figure 4 is a diagrammatic view of the lamp and suitable electrical connections for operating the same.

To illustrate my invention, I have shown on the drawing, a lamp 11 for artificially producing 50 daylight, said lamp comprising a plurality of separate sources of light of character adapted to combine to form approximate daylight.

The lamp 11 comprises envelope means 12 and 55 18 forming a plurality of sealed channels 13, 15,

and 17, adapted each to contain a suitable gaseous media adapted for excitation by electrical discharge therein to artificially produce a sunlight component. To this end, the channel 13 contains mercury vapor. The channel 15 contains cadmium vapor, preferably with gallium in sufficient quantity to provide, with the cadmium, a soft alloy when the ingredients solidify, as when the lamp is inactive for any length of time, and thus prevent cracking of the containing envelope. The channel 17 contains neon gas. The envelopes also have suitable electrode means associated therewith for the purpose of exciting the gaseous media in the channels 13, 15, and 17, and cause the same to glow and emit their corresponding sunlight components when electrical discharges take place through the excited gases functioning as conductors.

As is well known to those familiar with the phenomena of electrical discharge in gaseous conduction media, mercury vapor, when electrically excited by electrical discharge therein, produces a characteristic blue light; cadmium vapor produces a green light, and neon a red light, and it is the combination of the spectra of mercury vapor, cadmium, gallium vapor, and neon gas that gives the artificial daylight spectrum. By controlling the intensity of light produced by the excitation of the gaseous media in the several channels 13, 15, and 17, I am able to produce a synthetic light so closely approximating sunlight as to be substantially indistinguishable therefrom by normal human eyesight.

The light intensity produced by electrical discharge in a gaseous conduction medium varies as a function of current density of the discharge, which, in turn, depends upon the cross-sectional area and length of the discharge path, the applied potential causing the discharge, the character of the gaseous conduction media, and, in making my sunlight lamp, I prefer to take advantage of the foregoing conditions in order to produce a neat and compact device and to overcome several difficulties which present themselves in designing a lamp for practical use.

I may, of course, employ separate envelopes for the several conduction media and mount the several envelopes in close juxtaposition, the gas in each envelope being energized at the potential required to produce a desired intensity of illumination in each gaseous medium. I prefer, however, for reasons which will hereinafter be more fully explained, to form, as an integral cylindrical unit, the envelope means 18 defining the elongated cadmium-gallium vapor and mercury-containing channels 15 and 13, the integral unit being arranged so that the channels 13 and 15 extend in parallel relationship in the envelope, while the envelope 12, defining the neon channel 17, is formed as a separate element and mounted in position to encircle or embrace the envelope 18, the envelope 12, to this end, being preferably arranged in helical coils of a size adapted to snugly receive the cylindrical unit 18.

Cadmium, either alone or alloyed with gallium, and mercury, of course, are not normally gases and difficulty may be encountered in initiating and maintaining an electrical discharge in these media. In order to obviate the difficulty, I prefer to enclose, in the channels 13 and 15, a quantity of a suitable, preferably gaseous, carrier medium adapted to function as a conductor for the discharge until the mercury and cadmium, or cadmium-gallium alloy become vaporized to a degree enabling them to function as conduction

media, after which the heat of operation of the lamp will maintain these media in properly vaporized condition. Crypton, xenon, or argon gases may be thus employed in the channels 13 and 15 in conjunction with the mercury and cadmium-gallium alloy, since these gases, when excited, do not emit much light and hence will have little, if any, effect upon the resultant light emitted by the gases 13 and 15. I prefer, however, to use crypton gas, with mercury, since the same is relatively inexpensive. Crypton gas gives a faint bluish-pink light when electrically excited. I prefer to use xenon gas as a carrier for the cadmium or the cadmium-gallium alloy because of its low ionization potential and also because its atomic weight is close to that of cadmium. The amount of cadmium and mercury in the channels 15 and 13 respectively is such as will keep the crypton gas in saturated condition when the lamp is in operation.

Even where a carrier medium is thus utilized in the channels 13 and 15, it is ordinarily more difficult to initiate and maintain an electrical discharge in the channels 13 and 15, than it is in the channel 17 containing the neon gas. I consequently prefer to arrange the envelope 12, forming the channel 17, in such a way that said channel encircles and embraces the channels 13 and 15. This, as heretofore mentioned, may conveniently be accomplished by forming the envelope 12 as a preferably helically arranged tubular element, which may be assembled by merely sliding the same in place around the envelope means 18.

When the lamp is started in operation, the neon gas in the channel 17 is first excited by the initiation of electrical discharge therein and an electrostatic effect is thereupon induced in the channels 13 and 15, which partially excites the gases in said channels and facilitates the initiation of electrical discharge in said channels when a suitable electrical potential is applied to the partially excited gases. In this way, the arrangement of the neon-containing envelope 12 is utilized to aid the operation of the mercury and cadmium lamp portions and, although the envelope, forming the neon channel 17, may, if desired, be integrated with the envelopes forming the mercury and cadmium channels 13 and 15, in which case the neon channel may extend parallel with respect to the channels 13 and 15, I prefer to form the neon envelope as a separate element in order to facilitate the assembly thereof around the envelope means forming the channels 13 and 15; but I do not herein claim the broader aspects of invention relating to the use of an exciter for improving the operation of the gaseous conduction device, since the same forms the substance of my co-pending application, Serial No. 706,670, filed January 15, 1934.

I prefer also to make the discharge channel 17 considerably longer and of lesser cross-sectional area than the channels 13 and 15 in order to obtain a desired relative amount of red light in the channel 17 with respect to the blue and green light produced in the channels 13 and 15; and it is more convenient, therefore, to form the envelope 12 as a separate unit rather than integral with the envelope means defining the other channels 13 and 15.

I may also provide separate envelopes to define the channels 13 and 15 but prefer to employ integral envelope means 18 comprising a preferably cylindrical tubular envelope having a partition 19 therein with the channels 13 and 15

extending within the envelope and on opposite sides of the partition 19. This arrangement is desirable because the light sources are thus located as close together as possible. Moreover, the vaporization temperature of cadmium is relatively high and, by arranging the channels 13 and 15 in adjacent relationship, with only the partition 19 therebetween, the channel 15 will operate at a higher temperature than if the channels were separated. The arrangement thus assists in maintaining the cadmium in vaporized condition in the channel 15 when the device is in operation. If separate envelopes are employed, it is necessary to operate the cadmium channel 15 at a somewhat higher potential in order to generate additional heat to maintain the medium in vaporized condition. By forming the element 18, as illustrated, I am able to considerably increase the operating efficiency of the device.

The envelope element may be conveniently fabricated from cylindrical partitioned tubing of the character shown in Figure 1, wherein the integral portion is offset on one side of the longitudinal axis of the tubing to provide channels of unlike cross-section within the cylindrical envelope and on opposite sides of the partition. Tubing of this character may be conveniently fabricated in glass by the process taught in my Patent No. 1,904,348, issued April 18, 1933.

I prefer to operate the channels 13 and 15 in series, that is to say, with the same total current flow through each, and since it is necessary to maintain a somewhat higher temperature in the cadmium channel 15, than in the mercury channel 13, the cross-sectional area of the channel 15 is made somewhat smaller than that of the channel 13, so that the current density will be higher and heat produced will be greater. The ratio of the cross-sectional area of the channels 13 and 15 is preferably approximately as 342 is to 75, since I find that this ratio will afford a current density in the channel 15 sufficiently high to maintain the cadmium in vaporized condition during the operation of the lamp. At the same time, the mercury vapor channel cannot satisfactorily be operated at a current density as great as that which has to be maintained in the cadmium channel 15.

The ratio of area indicated above will furnish a suitable current density in each channel for maintaining the gases in proper condition for passing the operating discharge. Some of the heat, generated in the channel 15 by the relatively high current density prevailing therein, will escape through the partition means 19 separating the channels and will assist in maintaining the mercury vapor channel at a temperature slightly higher than would otherwise be the case where the channels 13 and 15 are formed in separate envelopes. The amount of heat thus escaping to the mercury vapor channel will aid in maintaining the mercury in vaporized condition and thus avoid the danger of impaired operation due to condensation of mercury vapor in the channel 13, which is likely to occur where the device is in operation under excessively low external temperature conditions. Moreover, the escape of heat from the channel 15 to the channel 13 assists in conditioning the vapor in the channel 13 for discharge current flow therein and permits the discharge to take place more easily, thus improving the operating efficiency of the device.

In order to energize the mercury vapor in the channel 13, I prefer to employ spaced-apart

electrodes, including a cathode electrode 21 at one end of said channel and anode electrodes 23 at the other. These anode and cathode electrodes may be of any suitable construction and are mounted in suitable housings 25 sealed to and communicating with the channel 13 at the opposed ends thereof.

For exciting the cadmium vapor in the channel 15, I prefer to employ a cathode electrode 27 and an anode electrode 29 at opposite ends of said channels, said electrodes 27 and 29 being of any suitable or preferred construction and mounted in suitable housings 31 formed at and communicating with the channel at opposite ends of the element 18. The cathode electrode 21 and the anode 15 electrode 29 are preferably mounted at the same end of the lamp element 18, while the anodes 23 and cathode 27 are mounted at the opposite end of the element in order to facilitate the electrical interconnection of the channels 13 and 15 in series, as by means of the conductor 33, connecting the anode 29 with the cathode 21.

As heretofore mentioned, the envelope 12 preferably comprises an elongated envelope arranged in helical fashion. Suitable electrodes 25 35, for energizing the gas in the channel 17, are disposed at opposite ends of the elongated envelope, said electrodes being disposed in suitable housing 37 disposed at the opposed ends of the envelope and sealingly connected with the channel 17. The electrodes 35 may be of any suitable or preferred character.

The neon gas, within the envelope 12, is energized from a suitable power source 39 through suitable conductors 41 interconnecting said power source with the electrodes 35. The cathode electrodes 21 and 27 also are or may be excited from suitable sources of cathode exciting power 43 and 45, the power source 43 being connected with the cathode 21 by means of the conductors 47, 40 while the power source 45 is connected with the cathode 27 by means of conductors 49.

Discharge-creating potential is applied to the gases in the channels 13 and 15 from a suitable power source 51, comprising, in the illustrated embodiment, the secondary winding of a transformer 53, the primary winding 55 of which is supplied with energy from a suitable power source through conductors 57, one of which is connected at one end of the winding 55, the other being connected on said winding at its mid-point. The opposite ends of the winding 55 also are or may be electrostatically connected together through a condenser 59.

The opposite ends of the secondary winding 55 51 are or may be connected by conductors 61 respectively with the anode electrodes 23, a condenser 63 being preferably interposed between the conductors 61. The winding 51 is provided with a tap at its mid-point, which is connected, 60 through a choke coil 65 and a control switch 67, to one of the conductors 49 leading to the cathode 21. The switch 67 remains normally open when the device is not in operation but is adapted to close automatically after a predetermined 65 interval following the application of operating energy from the power sources 43 and 45 to the cathodes 21 and 27. To this end, the switch 67 has a shiftable element controlled from a power source 69, so that the switch closes after a predetermined 70 interval following application of power from said source.

The power sources 39, 43, 45, and 69 may and preferably do comprise secondary windings of a transformer, the primary winding 71 of which is 75

supplied from a suitable source of energy through a switch 13, by means of which the lamp may be started in operation or stopped. In operating an actual lamp embodying the invention, the 5 windings 39, 43, 45, and 69 were arranged to deliver an alternating potential of 220 volts between the electrodes 35, a potential of $5\frac{1}{2}$ volts to energize the cathodes 21, and a potential of 1 volt, applied by means of the winding 69, in 10 order to actuate the time-delay switch 67. A suitable voltage was applied to the winding 55 by means of the conductors 57 to cause application of potential of the order of 100 to 200 volts alternately between the cathode 21 and each anode 23. 15 The vertical distance between the cathode 21 and the anode 29 was substantially equal to the vertical distance between the cathode 21 and each of the anodes 23, this dimension being about 50 centimeters in the actual lamp heretofore mentioned. The tube 18 had an inner diameter of 20 41.5 millimeters, while the partition, which was 1.5 millimeters in thickness was offset approximately 12 millimeters from the longitudinal axis of the cylindrical envelope 18. The channel 17 25 was 3.04 meters in length between the electrodes 35 and had an area of 28.27 square millimeters. The gas pressures in the channels 13, 15, and 17 were respectively $\frac{1}{2}$ millimeter, $\frac{1}{2}$ millimeter, and 11 millimeters.

30 It will be seen that, upon closure of the switch 13, electrical discharge may immediately be initiated in the neon element 17 and that the cathode-exciting current may be applied to the cathodes 21. The switch 67, however, may remain 35 open so that the potential will not be applied upon the gases in the channels 13 and 15. After a short time delay, during which the cathodes 21 and 27 become excited to operating condition and the electrostatic effect is established in the 40 channels 13 and 15 by the action of the neon element 17, the switch 67 will close and a potential applied alternately between the cathode 21 and each of the anodes 23. This will cause discharge to take place alternately from each of the anodes 45 23 to the cathode 21, and, since said cathode 21 is connected with the anode 29, a discharge will also take place through the gas in the channel 17 from the anode 29 to the cathode 27 contemporaneously with the discharges occurring through 50 the gas in the channel 13. In this fashion, the gases in the channels 13 and 15 may be made to glow with their respective colorations and at a desired density. At the same time, since the neon lamp 17 is in operation, a red light will be 55 emitted from this source, which, combining with the blue and green glows from the gases in the channels 13 and 15, will produce a compound light substantially identical to sunlight.

In operating the lamp, I find that the vapors 60 of cadmium and gallium in the channel 15 tend to collect in any portion of the channel 15, which operates at a lower temperature than other portions of the channel. Corners and electrode pockets tend to operate at a lesser temperature 65 than that prevailing in the channel intermediate the electrode pockets. In order to prevent the accumulation and condensation of cadmium vapor in the electrode pockets, I prefer to enclose the electrode pockets in a preferably cylindrical 70 shell of any suitable metallic substance, the inwardly facing surface of which may be polished to form a mirror adapted to reflect inwardly and maintain a temperature within the electrode pockets sufficient to prevent condensation of the 75 cadmium vapor at such places.

It is thought that the invention and numerous of its attendant advantages will be understood from the foregoing description and it is obvious that numerous changes may be made in the form, construction, and arrangement of the several 5 parts of the illustrated apparatus without departing from the spirit or scope of my invention or sacrificing any of its attendant advantages, the forms herein described being merely for the purpose of illustrating the invention. 10

Having thus described my invention, what I claim as new and desire to secure by Letters Patent is as follows:

1. A gaseous conduction device comprising 15 means forming a pair of adjacently extending elongated gaseous conduction elements, and an elongated embracing element arranged about said adjacently extending elements, wherein the adjacently extending elements contain gaseous conduction media of unlike character and adapted 20 when excited to produce a synthetic light of predetermined color characteristics comprising the combined spectrum of the light produced by the gaseous media in the several elements.

2. A gaseous conduction device comprising 25 means forming a pair of adjacently extending elongated gaseous conduction elements, and an elongated embracing element arranged about said adjacently extending elements, wherein the embracing element contains a gaseous conduction 30 medium adapted when excited to produce light having different spectrum characteristics from the spectrum characteristics of the light produced by the adjacently extending elements, whereby when all of the elements are excited the device 35 will produce a synthetic light comprising the combination of the spectrums of all of the elements.

3. A gaseous conduction device comprising 40 means forming a pair of adjacently extending elongated gaseous conduction elements, and an elongated embracing element arranged about said adjacently extending elements, wherein the embracing element embodies a noble gas as a conduction medium, one of the adjacently extending elements embodying mercury and the other a 45 noble gas with cadmium as conduction media.

4. A gaseous conduction device comprising 50 means forming a pair of adjacently extending elongated gaseous conduction elements, and an elongated embracing element arranged about said adjacently extending elements, wherein the embracing element embodies a noble gas as a conduction medium, one of the adjacently extending elements embodying mercury and the other a noble gas with gallium as conduction 55 media.

5. A gaseous conduction device comprising 60 means forming a pair of adjacently extending elongated gaseous conduction elements, and an elongated embracing element arranged about said adjacently extending elements, wherein the embracing element embodies a noble gas as a conduction medium, one of the adjacently extending elements embodying mercury and the other a noble gas with an evaporable metal as conduction 65 media.

6. A gaseous conduction device comprising a plurality of gaseous conduction elements, at least one of said elements comprising neon as a conduction medium, and being arranged in helical 70 coils embracing others of said elements, including an element embodying a noble gas with cadmium and gallium as a conduction medium and an element embodying mercury with a noble gas as a conduction medium.

7. A gaseous conduction device comprising a plurality of gaseous conduction elements, at least one of which comprises neon gas as a conduction medium and is arranged to embrace others of said elements, including an element embodying mercury and an element embodying a noble gas with cadmium and gallium as a conduction medium. 5
8. A gaseous conduction device comprising envelope means forming a pair of elongated gaseous conduction elements respectively comprising mercury and cadmium as conduction media, and extending in adjacent relationship, and an elongated element comprising neon as a conduction medium arranged in position embracing the other elements. 10
9. A gaseous conduction device comprising gaseous conduction means forming a pair of elongated gaseous conduction elements respectively comprising mercury and cadmium as conduction media, and extending in adjacent relationship, and an elongated element comprising neon as a conduction medium arranged in coils in position embracing the other elements. 15
- 25 10. A gaseous conduction device comprising envelope means defining a pair of channel portions, one of which contains mercury and the other cadmium as conduction media, and an envelope defining a channel containing gaseous neon as a conduction medium, said envelope being arranged to embrace the envelope means whereby, when electrical discharge is established in the gaseous contents of the envelope, the contents of the channel portions of the envelope means may 30 become excited.
11. A gaseous conduction device comprising envelope means defining a pair of channel portions, one of which contains mercury and the other cadmium as conduction media, said envelope means comprising an integral partition separating the channels whereby the heat, generated by electrical discharge in the medium in one channel, may assist in establishing electrical discharge in the other. 35
- 45 12. A gaseous conduction device comprising envelope means defining a plurality of chambers, a conduction medium comprising mercury in one of said chambers, a conduction medium comprising cadmium in another of said chambers, and a helix of neon embracing said chambers. 50
- 55 13. A gaseous conduction device comprising envelope means defining a plurality of chambers, a conduction medium comprising mercury and crypton gas in one of said chambers, a conduction medium comprising cadmium and xenon gas in another of said chambers, and a helix of neon embracing said chambers. 60
- 60 14. A gaseous conduction device comprising integral envelope means defining a plurality of chambers, a conduction medium comprising mercury in one of said chambers, a conduction medium comprising cadmium in another of said chambers, and a separate envelope, comprising a tube, coiled about said envelope means and defining a channel containing neon gas. 65
- 70 15. A gaseous conduction device comprising means forming a pair of elongated gaseous conduction elements respectively comprising mercury and cadmium together with appreciable amounts of gallium as conduction media, said elements extending in adjacent relationship, and an elongated element comprising neon as a conduction medium, arranged in position embracing the other elements. 75
16. A gaseous discharge device comprising envelope means having an integral partition defining a plurality of elongated chambers of unlike cross-sectional area within the envelope means on opposite sides of the partition, and a gaseous conduction medium in each chamber and separated by said partition. 80
17. A gaseous discharge device comprising envelope means defining a plurality of adjacent channel portions adapted to be electrically interconnected in series, in which the cross-sectional areas of said channel portions have the approximate ratio 456/100. 10
18. A gaseous conduction device comprising a sealed envelope having an integral internal partition defining a pair of elongated gaseous conduction channels within the envelope on opposite sides of the partition; and an elongated gaseous conduction element arranged about said adjacent extending channels. 15
19. A gaseous conduction device comprising a sealed envelope having an integral internal partition defining a pair of elongated gaseous conduction channels within the envelope on opposite sides of the partition and an elongated gaseous conduction element arranged about said adjacent extending channels, wherein said extending channels are of unlike cross sectional area. 20
20. A tubular element having an integral partition offset on one side of the axis of the element to define channels of unequal cross-sectional area 30 of the element on opposite sides of the partition, gaseous conduction media of unlike character in the said channels, and means to electrically interconnect the gaseous conduction media in series and to apply electrical potential across said series arrangement, whereby to obtain a desired current density in the gaseous media in said channels. 35
21. A device as set forth in claim 20 including a gaseous conduction device encircling and embracing said tubular element whereby when energized to aid in the excitation of the media in said channels. 40
22. A gaseous conduction device comprising a plurality of gaseous conduction elements, at least one of which comprises neon as a conduction element and is arranged in helical coils embracing others of said elements, including an element embodying a noble gas with cadmium as a conduction medium and an element embodying mercury. 45
23. A gaseous conduction device comprising a plurality of gaseous conduction elements, at least one of which comprises neon as a conduction element and is arranged in helical coils embracing others of said elements, including an element embodying xenon with cadmium and an element embodying mercury as a conduction medium. 55
24. A gaseous conduction device comprising a plurality of gaseous conduction elements, at least one of which comprises neon as a conduction element and is arranged in helical coils embracing others of said elements, including an element embodying a noble gas with cadmium and a trace of gallium as a conduction medium and an element embodying mercury. 60
25. In combination, a discharge device comprising means forming a discharge channel containing a gas adapted to sustain electronic discharge when excited, means to excite said gas comprising a sealed tubular member arranged about the discharge device in position to embrace the same, said tubular member containing gaseous means adapted to carry high frequency electrical oscillations means to generate oscillations in said tubular member whereby to electro- 65

- statically energize said gas, and electrode means cooperatively associated with said discharge device to apply discharge creating potential to said gas in said channel.
- 5 26. In combination, a discharge device comprising means forming a discharge channel containing a gas adapted to sustain electronic discharge when excited, and means to excite said gas comprising a sealed tubular member arranged 5 in helical form around the discharge device and containing gaseous means adapted to carry high frequency electrical discharge oscillations, means to initiate high frequency oscillations in said tubular member in order to electrostatically energize the gas in said discharge channel, and electrode means cooperatively associated with said discharge device to excite the gas in said channel.
27. A discharge device comprising an envelope 20 defining an elongated channel containing a gaseous medium adapted to glow and emit light when electrically excited, means forming a second discharge channel containing a gaseous medium adapted to glow when excited and emit light of 25 a color contrasting with the light emitted from the first mentioned channel, said second channel encircling said first channel, and means to create high frequency discharges in said second channel to cause the medium therein to glow and to subject the gaseous medium in the first channel to the electrostatic effect of the high frequency discharges in said second channel whereby to facilitate the excitation of the medium in the first channel.
- 30 28. In combination, a pair of cooperatively associated discharge elements, said elements each comprising envelope means defining sealed channels containing gaseous media adapted to glow when electrically excited, and one element forming parallel adjacent channel portions, the other element having its channel embracing the channel portions of the first element whereby the operation of the embracing element may electrostatically excite the gaseous media in said channel portions.
- 35 29. In combination, a pair of cooperatively associated discharge elements, the first adapted for operation at relatively low voltage with relatively large consumption of power, and the second one at least partially encircling the first one and adapted for operation at relatively high voltage with relatively low power consumption, both of said elements comprising envelope means defining sealed channels containing gaseous media 40 adapted to glow when electrically excited, and the first element forming parallel adjacent channel portions, said second element having its channel helically disposed about the channel portions of the first element.
- 45 30. In combination, a discharge device comprising means forming a discharge channel containing a gas adapted to sustain electronic discharge when excited, means to excite said gas comprising a sealed tubular member arranged 50 about the discharge device in position to embrace the same, said tubular member containing gaseous means adapted to carry high frequency electrical oscillations, means to generate oscillations in said tubular member whereby to electrostatically energize said gas, and electrode means cooperatively associated with said discharge device to apply discharge creating potential to said gas in said channel, said electrode means comprising spaced apart cathode and anode means opera- 55 tively associated with said channel.
31. In combination, a discharge device comprising means forming a discharge channel containing a gas adapted to sustain electronic discharge when excited, means to excite said gas 10 comprising a sealed tubular member arranged about the discharge device in position to embrace the same, said tubular member containing gaseous means adapted to carry high frequency electrical oscillations, means to generate oscillations 15 in said tubular member whereby to electrostatically energize said gas, and electrode means cooperatively associated with said discharge device to apply discharge creating potential to said gas in said channel, said electrode means comprising 20 a cathode at one end of said channel and a plurality of spaced anodes operatively associated with said discharge channel and spaced from said cathode.
32. In combination, electrical discharge means 25 forming discharge channel portions containing gaseous media adapted to sustain electronic discharge when excited, a sealed tubular member arranged about said channel portions in position to embrace the same, said tubular member 30 containing gaseous means adapted to glow when excited and emit light, said gaseous means being also adapted to carry high frequency electrical discharge currents, means to utilize said currents in said tubular member whereby to electrostatically energize the gaseous media in said channel portions, and electrode means cooperatively associated with said channel portions to apply discharge creating potential to the gaseous media 35 therein, said gaseous media, when excited, being 40 adapted to emit light of predetermined spectrum characteristics which, together with the light emitted by the gaseous means in the tubular member, provides a synthetic light of a desired spectrum.
33. A discharge device comprising an envelope 45 defining channel portions containing gaseous media adapted to be energized to sustain electrical discharge therein, said channel portions being disposed adjacently with dielectric means 50 therebetween, spaced electrodes communicating with said adjacently disposed portions to energize the gaseous media therein, and an exciter comprising a gaseous conduction device operatively associated with said adjacently disposed 55 channel portions.
34. A discharge device as set forth in claim 33, wherein the gaseous conduction exciter comprises a tubular element having portions disposed around and about said envelope, the conduction 60 media in said channel portions and in the tubular exciter element being pre-selected to provide combined light of a desired spectrum when excited.
35. The combination as set forth in claim 28, wherein the element which embraces the adjacent channel portions is arranged in helical form.

ROBERT E. BARCLAY.
